UNITED STATES PATENT OFFICE.

ISAAC BENJAMIN JEFFRIES, OF LLANELLY, WALES.

AIR-TUBE FOR PNEUMATIC TIRES AND PROCESS OF MANUFACTURING THE SAME.

1,309,687.

Specification of Letters Patent. Patented July 15, 1919.

Application filed August 24, 1918. Serial No. 251,205.

To all whom it may concern:

Be it known that I, ISAAC BENJAMIN JEFFRIES, known and trading as ISAAC BENJAMIN, subject of the King of Great Britain and Ireland, residing at 3 John street, Llanelli, in the county of Carmarthen, Wales, have invented an Improved Air-Tube for Pneumatic Tires and Processes of Manufacturing the Same, of which the following 10 is a specification.

The invention relates to that type of air tube in which long strips of thin rubber are fixed in the interior thereof, each strip overlapping the adjacent strip and being cut 15 from the loose edge toward the edge which is fixed to the tube, so as to form separate flaps. The strips have been fixed both longitudinally and transversely.

It has been proposed to cement or vulcanize such strips in position. Such strips were cut from vulcanized rubber and had square edges and did not fit closely against each other, so that on a puncture taking place, the flap beneath the puncture had to be bent by 20 the outflowing air before it came in contact with the body of the air tube or with an underlying flap, and as a matter of fact the flap did not always bend sufficiently to make a tight joint and allowed air to escape. It 25 must be remembered that such flaps, standing up slightly and not being in contact, would have an equal air pressure on both sides thereof.

According to the present invention I attach the strips of rubber to a foundation by the following method.

The foundation is a sheet of unvulcanized rubber, and the strips are likewise unvulcanized rubber. Each strip is placed in position on the foundation and is pressed or rolled into contact therewith. The strips are cut into flaps, either subsequently to or previously to being fixed to the foundation. The strips having all been placed upon the foundation and overlapping each other as usual, the whole is then placed upon a mandrel which is circular in cross section, the strips being in contact with the mandrel. The foundation is bound with canvas, there- 45 by applying pressure to the foundation and strips. This pressure has the effect of squeezing the fixed square edges of the strips into feather or wedge shaped edges, and it further has the effect of squeezing the strips 50 into close contact with and into the body of

underlying strips, so that the whole has a smooth interior surface when vulcanized and removed from the mandrel. It will be understood that the loose portions of the strips are prevented from adhering to each other 60 by French chalk or the like.

By this process, it will be observed that the strips and flaps are formed on the mandrel so as to take up as nearly as possible the precise form required of them, when 65 fulfilling their purpose of effectively sealing a puncture, for when pressed against the surface of the air tube by air pressure, each flap has then almost precisely the same position and shape given to it as that obtained 70 by being formed on the mandrel. If a mandrel of ring shape is used as hereafter mentioned, the fit is exceedingly close, because in that case each flap is given not only the proper transverse curvature, but also the 75 correct longitudinal curvature. If a straight cylindrical mandrel is employed this longitudinal curvature is not obtained. However having regard to the shortness of the flaps, the loss of efficiency by using a straight cy- 80 lindrical mandrel for large tires, is not substantial enough to affect seriously the utility of my invention.

The foundation with the strips vulcanized thereon as above described, may be attached 85 to an air tube which has been turned inside out, and it may project at one end beyond the tube. The projecting end carrying its strips, after the tube has been again turned, can easily be inserted into the other end of 90 the tube when the ends of the air tube are being joined. This projecting end overlaps the strips in the other end of the tube, thus leaving no part of the tube unprotected by flaps. 95

The foundation, instead of being attached to an air tube, may itself form the body of the tube. In this case the mandrel or former is of ring form and I preferably employ separate portions of foundation with 100 unvulcanized strips attached, which portions are so placed upon the mandrel or former that their edges and the edges of the strips are in contact and are vulcanized together as the strips are being vulcanized to the foun- 105 dation. By using separate pieces of foundation it obviates the necessity of stretching them to any great extent, which may disarrange the flaps, and the result is superior to a tube built up with a single piece of founda- 110

tion. The foundation may be sufficiently thick to form the body of the air tube or, if too thin for that purpose, it may be covered with a sheet of rubber to produce the desired thickness, the whole being vulcanized together in the one operation.

The strips thus vulcanized together become endless. Instead of attaching strips to the portions of foundation, I may employ strips which are sufficiently long to pass longitudinally or circumferentially around the ring shaped mandrel. The ends of each strip are joined by butting them together or forming a scarf joint. The strips being properly arranged upon the mandrel to partly overlap each other, are then covered with portions of foundation of such a shape that their edges are in contact, and the whole is vulcanized together under pressure.

The result is that I produce an endless ring covered entirely on the interior with closely fitting flaps, or on that part which will come next to the road surface. This ring is open on the inner side, as the edges of the foundation come down the sides of the mandrel or former but do not touch each other. The air tube is completed by joining the edges in any usual manner.

One advantage of this last described method of producing an air tube is that the interior can be readily examined to ascertain if all the flaps are properly in position before the edges of the foundation are connected to form it into a tube.

Another advantage is that a lighter air tube can be produced, as the foundation itself forms the body of the air tube.

Further, this method of manufacture is quicker than that first above described in which the foundation is fixed in a tube, especially if known non-drying material such as glycerin or soft soap be placed in the air tube, as it can be placed in the tube before the edges of the foundation are connected, whereas by the first described process it was necessary to turn the tube inside out before applying the non-drying material and then to re-turn the air tube.

If desired a tube made according to the present invention may be provided with male and female ends or butt ends of any suitable design.

The invention is illustrated in the accompanying drawings, in which:—

Figure 1 is a longitudinal section through a part of the foundation and strips before vulcanization.

Fig. 2 is a longitudinal section of part of an air tube showing an internal view of the foundation with strips attached thereto.

Fig. 3 is a longitudinal section through part of a ring shaped mandrel or former showing the strips and foundation bound thereon ready for vulcanizing.

Fig. 4 is a transverse section of the man-

drel with foundation and strips thereon, these latter being shown diagrammatically.

Fig. 5 is a longitudinal section of an air tube which is joined by inserting one end within the other end. 70

Fig. 6 is a longitudinal section of an air tube the ends of which abut.

In Figs. 5 and 6 the strips are shown diagrammatically and the short portions of the tube are shown straight. 75

Fig. 7 is an enlarged cross section showing how the strips are squeezed together in the vulcanizing process.

Fig. 8 is a perspective view of the foundation when removed from a ring shaped 80 mandrel or former, and

Fig. 9 is a side elevation showing the foundation formed into a tube.

Fig. 10 is a perspective view of a short length of foundation provided with longitudinal or circumferential strips. 85

a, a, are the strips of unvulcanized rubber, which are cemented to the foundation *b* by their edges *a'*, as shown clearly in Fig. 1. This figure also illustrates the position 90 which strips of vulcanized rubber assume when they are cemented or even vulcanized to a vulcanized foundation. It will be noticed that they are not in close contact and if left so permanently in order to prevent 95 the escape of air through a puncture, they must be deflected by the outgoing flow of air, an effect which is very uncertain to attain.

The strips *a, a*, are cut at *a²*, from their 100 loose edges toward the fixed edges *a'*, in the usual manner. The foundation *b* with its strips *a*, is then applied to a mandrel or former *c*, the strips *a* being in contact with the mandrel or former. Canvas *d* is then 105 bound tightly around the foundation *b* and mandrel or former *c*, as shown in Figs. 3 and 4 in like manner to that in which it is bound around an ordinary air tube in course of manufacture. 110

The result is that the unvulcanized strips *a* are squeezed into the shape shown in Figs. 2, 3 and 7, and when vulcanized, permanently retain that form, having feather or wedge shaped edges and presenting a perfectly smooth surface with all the flaps in close contact. When such a foundation is punctured the flaps are already in position to close the aperture or passage and require no deflection whatever. 115

As shown in Fig. 4 the foundation *b* generally extends on one or both sides beyond the strips *a*. One edge *b²* may be trimmed off, lapped over the other edge *b³*, and be vulcanized in position as shown in Fig. 9, 125 when it is desired to form the foundation *b* into an air tube; or both edges may be trimmed and caused to abut.

When the foundation and strips are taken off the mandrel *c*, they may be carefully ex- 130

amined both inside and out to see that there are no faults in manufacture before the foundation is formed into a tube.

If it is desired to apply a non-drying material such as glycerin or soft soap to the strips *a*, it may also be applied before the edges of the foundation are connected.

If the mandrel *e* be of ring form, the foundation *b* is endless as shown in Fig. 8 and becomes a finished tube when the inner edges have been connected.

It may, however, be desired to fix a foundation *b* carrying strips *a*, within a tube already manufactured. Such a construction is shown in Figs. 5 and 6. The air tube *e*, *e'*, is turned inside out and a foundation *b*, carrying its strips *a*, is cemented or vulcanized on that part of the tube which is to be toward the road surface. One end of the foundation *b*, carrying its strips *a*, is allowed to loosely project beyond one end *e'* of the tube. This loose end is marked *b'* in Figs. 5 and 6, and when the ends *e*, *e'* of the tube are connected, it overlaps the strips *a* in the other end *e* of the tube. These last mentioned strips do not need to extend as far as the end *e'* of the tube, as shown in Fig. 5, thus providing room for the entrance of the end *e'* of the tube. A certain distance may be left between the end *e'* and the foundation *b* in the end *e*, thus insuring that the end *e'* does not disturb the flaps *a*, *a* in the other end *e*. This unprotected part of the end *e* is, however, protected by the overlapping loose projecting part *b'* of the foundation.

I claim:—

1. A process of manufacturing a pneu-

matic tube of the character described which consists is cementing unvulcanized strips of 40 rubber to an unvulcanized foundation, cutting the loose edge of the strips toward the fixed edge to produce flaps, placing the strips in contact with a mandrel, and then applying pressure to the exterior foundation 45 and vulcanizing the same.

2. An improved process for manufacturing an air tube as embodied in claim 1 in which the mandrel is of ring formation and the edges of the foundation extend down 50 the sides of the mandrel but are spaced apart, and are subsequently connected.

3. An improved air tube for a pneumatic tire made according to the process claimed in claim 1, in which the strips are vulcanized 55 on to a foundation which is fixed in the interior of an air tube and one end of the foundation is allowed to project from one end of the air tube so that it may overlap the strips in the other end of the air tube 60 when the two ends of the air tubes are connected, substantially as shown and described.

4. An improved process of manufacturing a pneumatic tube as embodied in claim 1 wherein the unvulcanized strips are arranged circumferentially of the mandrel and the ends of the strips are vulcanized together.

In testimony whereof I have signed my name to this specification in the presence of 70 two subscribing witnesses.

ISAAC BENJAMIN JEFFRIES.
